US0D1013578S

(12) **United States Design Patent** (10) Patent No.: **US D1,013,578 S**
(45) Date of Patent: ** Feb. 6, 2024

(54) **MOTOR VEHICLE**

(71) Applicant: **VOLKSWAGEN AKTIENGESELLSCHAFT**,
Wolfsburg (DE)

(72) Inventors: **Jozef Kaban**, Wolfsburg (DE); **Felipe Montoya Bueloni**, Wolfsburg (DE);
Einar Castillo Aranda, Wolfsburg (DE)

(73) Assignee: **VOLKSWAGEN AKTIENGESELLSCHAFT**,
Wolfsburg (DE)

(**) Term: **15 Years**

(21) Appl. No.: **29/842,160**

(22) Filed: **Jun. 10, 2022**

(30) **Foreign Application Priority Data**

Dec. 10, 2021 (DE) 40 2021 101 136.6

(51) LOC (14) Cl. **12-08**

(52) U.S. Cl.

USPC **D12/99**; D12/90
